INSTRUMENT FOR TUFTING MATTRESSES
OR THE LIKEJesse E. Zofnass, Boston, Mass., assignor to New
York Mattress Company, Boston, Mass., a cor-
poration of Massachusetts

Application February 13, 1933, Serial No. 656,465

2 Claims. (Cl. 112—3)

This invention relates to the tufting of mattresses or similar resiliently compressible objects. After the various parts of a mattress have been assembled, it is the practice to tie the ticking 5 of both faces together at suitably spaced points, by means of thread or the like, so as to enhance the resiliency of the mattress, as well as to minimize the chances for localized distortion therein. The mattress thus becomes indented at spaced 10 points in both its surfaces, and this makes for an ornamental, tufted appearance. This work has heretofore been done while the mattress was supported on a stationary table. While thus supported, widely spaced stitches were made 15 through the mattress body with an elongated sewing needle. After a number of stitches were thus formed at spaced points through the mattress body, the operator would cut the thread connecting the stitches, pull hard on the ends of 20 each stitch, and then tie them together, thereby locally compressing the mattress and forming indentations in its surfaces. Aside from the fact that such work requires skilled operators, it is time-consuming, expensive, and, unless care- 25 fully done, results in a non-uniform tufted effect.

The chief object of the present invention is to facilitate the production of tufted mattresses of the foregoing type and to enable unskilled 30 operators to perform the work quickly and perfectly with a minimum of exertion. In accordance with the present invention, the mattress is first compressed substantially uniformly between separable, locked frames having openings there- 35 through, through which the mattress body is ex- posed so as to permit an operator to tie the tick- 40 ing of both faces together at the appropriate points. While thus compressed, loops of thread whose ends are untied are passed through the body of the mattress, whereupon the ends are tied, tightly together with little, if any, tension, and the mattress is then permitted to expand by 45 unlocking and separating the frames. Upon ex- pansion of the mattress, indentations are formed 50 where the ticking of both faces has been tied together, so as to furnish the desired tufted ap- 55 pearance. I have provided a novel and simple instrument for passing a loop of thread through a mattress body in a single stroke. The instru-

the needles are going through the mattress body, suitable means carried by the instrument hold the bend of the loop against the mattress, thereby preventing slippage or displacement of the thread. 60

With the foregoing and other features and ob- jects in view, the invention will now be described in greater detail in conjunction with the accom- 65 panying drawings, wherein

Figure 1 shows in perspective the upper and lower mattress-compressing frames separated from each other.

Figures 2, 3 and 4 represent transverse sections through the frames at various stages of locking, 70 with a mattress inserted therebetween.

Figure 5 is a side view of the locked frames tilted to an upright position.

Figure 6 shows in perspective a lever for facil- 75 itating the compression of the mattress and the locking of the frames.

Figure 7 illustrates in perspective a finished, 80 tufted mattress.

Figure 8 is a front view, partly in section, of the instrument for passing a loop of thread through the body of the mattress.

Figures 9, 10, 11 and 12 are sectional details showing a loop of thread at different stages of formation in the body of the mattress.

Figures 13 and 14 represent sections through the instrument on the lines 13—13 and 14—14, 85 respectively, of Figure 8.

Referring now in detail first to Figure 1 of the drawings, 1 represents the lower frame, which is of generally rectangular form and of a size capable of supporting thereon a mattress 2, as shown in Figure 2. The frame includes slats 3 extending in spaced, parallel relation from one side of the frame to the other. The ends of the frame are shown provided with trunnions 4 rotatable in bearings 5 afforded by standards 6. The upper frame 7 is constructed like the lower frame and, when separated from the lower frame, as shown in Figure 1, may be suspended near each corner as on ropes 8. These ropes are shown passing over pulleys 9 and carrying at their upper ends 90 weights 10 serving to raise the upper frame sufficiently to permit an operator to place a mat- 95 tress on the lower frame without interference by the upper one. Each rope 8 is shown with a hook 11 at its lower extremity loosely engaging in a staple 12 affixed near each corner of the upper frame. The pulleys 9 may be supported on suit- 100 able hangers (not shown) anchored to the ceiling or walls of the room.

Having placed a mattress 2 on the lower frame, 110

as shown in Figure 2, the operator pulls down the upper frame 7, releases it from the hooks 11, and proceeds to lock the upper frame to the lower one. To permit such locking of the frames, the 5 upper frame may have swivels secured near each of its corners a hook 13 adapted to engage in an eye member 14 secured near each corner of the lower frame. The frames may first be locked on their left-hand side, as shown in Figure 2, with 10 the upper frame assuming an inclined position, whereupon, the right-hand side of the upper frame member 7 must be forced downwardly against the mattress to compress the mattress uniformly throughout before complete locking of 15 the frames can be effected. Inasmuch as considerable force is required so to compress a mattress, suitable means may be provided to make this easy for the operator. Thus, as shown in Figure 1, each end of the lower frame may be 20 provided with an upstanding bar 15 whose upper end is provided with an aperture 16. The upper frame need be forced downwardly by the operator only to the point when the aperture 16 is above the frame, whereupon, a lever 17 having a 25 cam-shaped lower end portion 18 and a pin 19 projecting from the end of said portion may be brought to bear against the upper frame. This is done by inserting the pin 19 into the aperture 16 so that the portion 18 engages the upper 30 frame, and then pulling on the lever 17 in the direction of the arrow shown in Figure 7. The lever 17 thus affords the mechanical advantage of a wedge and enables the right-hand side of the frames to be brought together and locked, as 35 shown in Figure 4, without the exertion of an undue amount of effort by the operator. The mattress confined in compressed condition between the two frames may be tilted to the vertical position shown in Figure 5, so as to permit 40 easy access to all exposed regions of the mattress by the operator.

The operator can then proceed to pass loops of thread having untied ends at properly spaced intervals through the body of the compressed 45 mattress exposed through the frames. The instrument for so doing, as shown in Figure 8, comprises a handle 20 to which is affixed in spaced, parallel relation elongated needles 21, as by set-screws 22 entering into its sides, as best shown in 50 Figure 14. The handle may be cylindrical, as shown, or of any other suitable shape. The inactive upper end portions of the needles are slidably received within suitable openings formed in the handle, wherefore, should the needles 55 break in service, they may be removed from the handle and replaced by new ones. The needles may be of substantially cylindrical cross-section, excepting near their sharp lower ends, whereat they have enlarged and flattened out portions 23, 60 with eyes 24 formed therethrough. Bridging the needles immediately above their enlarged portions 23, is a plate 25, which is apertured so that the needles pass loosely therethrough, as shown in Figure 13, and which is reciprocatable on the 65 needles between their enlarged portions 23 and the lower end of the handle 20. The plate 25 is carried by the lower end of a rod 26, which passes through a central hollow 27 formed in the handle and thence through an opening 28 formed as a 70 continuation of the hollow 27 through the upper end portion of the handle but of sufficiently restricted size so that a tight bearing 29 for the rod is formed in the handle. The rod 26 is surrounded by an elongated compression spring 39, 75 which reacts between the bearing 29 and the

plate 25. It is thus seen that the rod is free to reciprocate and that by moving the plate 25 toward the handle, as is the case when the needles pass through a mattress body, the spring 29 is put under compression. The plate 25 also serves as a means for holding the lower end portions of the needles in the desired spaced relationship.

Thread, cord, tape, twine, or other suitable strand material 30 is passed through the eyes 24 of the needles to form a loop, as shown in Figure 8. With the mattress confined and compressed between the frames, as shown in Figure 5, the operator takes hold of the handle 20 and forces the needles 21 through the body of the mattress, which, as shown in Figure 9, may include the ticking 31, felt or batting 32, and compression springs 33 arranged in separate cloth cells or compartments 34. The mattress may, of course, be constructed in any other conventional way. The plate 25 holds the bend 35 of the loop against the face of the mattress as the needles are proceeding through the body of the mattress, thereby preventing slippage or displacement of the thread. This holding of the thread against displacement is made possible by the compression which the 100 spring 27 undergoes as the plate 25 and the rod 26 are forced upwardly by the downward movement of the needles through the body of the mattress. When the needles have proceeded through the mattress body sufficiently to have the ends of the loop come out of the eyes of the needles, as shown in Figure 10, the handle 20 may be pulled so as to retract the needles from the mattress body, thereby leaving a loop of thread with its untied ends hanging loose, as shown in Figure 11. These ends are tied together tightly into a knot 37, as shown in Figure 12, so that when the frames are unlocked and separated and the mattress permitted to expand, indentations will be formed in the surfaces of the mattress where the ticking has been tied together and the tufted 110 appearance shown in Figure 7 will result.

The upper frame 7 may carry permanent marks at the desired places, to guide the operator as to where loops of thread are to be passed through the mattress body. After the desired number of loops have been passed through the mattress body held in confinement between the frames, as shown in Figure 5, the ends of all the loops may be tied, whereupon the frames may be unlocked and separated so as to permit removal of the mattress. It is preferable that the mattress be compressed substantially to the limit of its resiliency between the compressing frames, as this not only enhances the tufted effect subsequently realized, but makes it easy to pass the needles through the mattress body, as there is no resiliency therein to oppose the pressure exerted thereon by the plate 25, which holds the bend of the thread loop against slippage. The thread may, of course, be readily pre-cut to lengths such that the ends of the loops formed therefrom and passed through the mattress body may be easily tied together into knots by the operator.

I claim:—

1. An instrument of the class described, comprising a handle, a pair of elongated needles extending in spaced, parallel relation from said handle and having eyes adjacent to their piercing ends through which a thread may be passed to form a loop, a plate reciprocally mounted between said needles and adapted to bear on the bend of a thread loop as it is being passed by said needles through a body, and a compression spring arranged in back of said plate and in between said 145 150

needles and reacting upon the passage of said needles through a body to exert yielding pressure on said plate.

2. An instrument of the class described, comprising a handle, a pair of elongated needles extending in spaced, parallel relation from said handle, said needles having enlarged portions near their piercing ends and having eyes at said portions through which a thread may be passed to 10 form a loop, a plate bridging said needles and slidable thereon between said enlarged portions and said handle, a reciprocatable rod arranged in

between said needles and extending in parallelism therewith, one end of which rod carries said plate and the other end portion of which rod passes through said handle, and a compression spring encompassing said rod and arranged to react between said plate and said handle, whereby when a thread loop is being passed by said needle through a body, said spring becomes compressed to exert yielding pressure on said plate as the latter bears on the bend of the thread loop. 85 85
